CLAIM

The ornamental design for a telephone booth, as shown and described.

DESCRIPTION

FIG. 1 is a perspective front view of a telephone booth showing our new design with a door shown in a closed position;

FIG. 2 is a perspective rear view thereof;

FIG. 3 is a front view thereof;

FIG. 4 is a rear view thereof;

FIG. 5 is a left side thereof;

FIG. 6 is a top plan view thereof; and,

FIG. 7 is a bottom view thereof.

The broken lines depicting the remainder of the telephone booth show features that form no part of the claimed design.

1 Claim, 7 Drawing Sheets
